CLAIM

USPC D24/108, 111–115, 117, 127, 152, 176,

The ornamental design for oral irrigator as shown and described.

D24/231; D4/100, 101, 102, 110, 111,

DESCRIPTION

D4/136, 138, 199

CPC ... A61C 15/046; A61C 15/047; A61C 15/048;

1. Oral irrigator

A61C 17/00; A61C 17/005; A61C

1.1: Front

17/092; A61C 17/02; A61C 17/0202;

1.2: Back

A61C 17/0205; A61C 17/0208; A61C

1.3: Top

17/0211; A61C 17/06; A61C 17/08; A61C

1.4: Bottom

17/16; A61C 17/22; A61C 17/221; A61C

(Continued)

17/222; A61C 17/225; A61C 17/227;

A61C 17/228; A61C 17/28; A61C 17/32;

1.5: Right

1.6: Perspective

The left view is omitted because it is a mirror image of the right view.
